UNITED STATES PATENT OFFICE

HEIMER W. MONSON, OF PORTSMOUTH, OHIO, ASSIGNOR TO WHEELING STEEL CORPORATION, OF WHEELING, WEST VIRGINIA, A CORPORATION OF DELAWARE

METAL SHIPPING CONTAINER

Application filed May 29, 1931. Serial No. 540,956.

This invention relates to closure constructions for replaceable head metal containers.

For economical reasons it is desirable to use metallic containers repeatedly, and therefore they are provided preferably with replaceable heads which can be quickly and easily attached and removed, and which will afford an effective and safe seal when in place. Furthermore, such containers are subjected to all kinds of conditions and rough handling. It is necessary, therefore, that they be strongly constructed, especially at the chimes, where heavy impacts are often received.

A characteristic of the closure constructions heretofore available, adapted to easy attachment and removal, is that not only do they not strengthen the end of the container, but also they present additional faces and projections subject to damage or destruction. This has been a serious disadvantage because the container may be thus rendered useless through inability to replace the heads.

It is among the objects of this invention to provide a closure for metallic containers which is adapted to easy and rapid attachment and removal of the head, tightly seals the container without danger of loosening of the head, reinforces the end of the container, can be conveniently repaired in case of damage, and has no loose connecting or fastening parts. Other objects and advantages will appear hereinafter.

In the accompanying drawings, Fig. 1 is a side elevation of a metal container, partly in cross section, showing the preferred embodiment of the invention; Fig. 2 an enlarged fragmentary cross section of a portion of the closure shown in Fig. 1; Figs. 3 and 4 fragmentary cross section and side elevational views, respectively showing details of the head construction; Figs. 5 and 6 fragmentary views similar to Figs. 3 and 4 showing details of construction of the open end of the drum; Fig. 7 a side elevation of the upper end of a drum, partly cut away, showing a tool for attaching and removing the head; and Fig. 8 a plan view of the tool shown in Fig. 7.

In accordance with this invention the open end of a metal container is closed by a head having a side wall telescoping in the end of the container. The side wall is continued outwardly from its upper end over a peripheral lip surrounding the container opening, and is then bent downwardly. This continuation of the side wall forms with the lip an annular recess within which a gasket can be pressed, and its lower end forms a skirt surrounding a reinforcing ring held disposed about the container below the tip. The head is held in sealing engagement in the container by means of gripping lugs formed in the skirt which cooperate with cam-acting bosses struck out of the reinforcing ring.

The invention may be described more in detail by reference to the drawings. As there shown, a metallic container 1 has an integral lip 2 surrounding its open end, and encircling the container directly beneath the lip is a reinforcing ring 3 held against the under side of the lip by any suitable means, such as a bead or swell 4 formed in the container wall. Bosses 5 are struck out from ring 3 at spaced intervals. The free edges 6 of bosses 5 are disposed at an angle to the plane of the container opening, as shown in Fig. 6, to provide cam surfaces for complementary members associated with the head 80 for drawing it tightly upon the container and securing it in place.

The container is provided with a head 7 adapted to fit within the open end of the container in a customary manner. As is shown in Fig. 2, the head is provided with an upwardly extending side wall 8 integral with the body of the head and adapted to telescope within the container opening. At its upper end side wall 8 is bent outwardly to form a top extension overlying lip 2, and is then bent downwardly to form a skirt 9 surrounding ring 3. There is thus formed an annular recess between the side wall extension and the lip in which there is disposed a sealing gasket 10. The gasket preferably is pressed into the recess so as to remain in the corner formed between the side wall and its extension when the head is 100

removed. This prevents damage to and loss of the gasket.

At spaced intervals the edge of the skirt is shaped to form inwardly extending gripping lugs 11 shaped as shown in Figs. 3 and 4. These lugs correspond in number and are complementary to bosses 5, so that they engage the cam edges of the bosses when the head is placed on the container and rotated in the appropriate direction.

To facilitate turning the head on and off the container, it is provided with openings 12 which can be engaged by a bar 13 used as a lever. This bar comprises handle portion 14 projecting beyond the container in order to give leverage in turning the head, a finger 15 secured to the bar near one end and adapted to engage an opening 12, and a similar finger 16 near the opposite end of the bar extending through a slot 17 wherein it can be secured at variable distances from the head by means of a wing nut 18. In using the bar, finger 15 is first inserted in an opening 12, finger 16 being positioned at the outer end of the slot. Finger 16 is then slipped along in the slot until its lower end extends into the opposite opening 12. Wing nut 18 is tightened to hold the finger in place, and the bar is ready for use. Although it is to be understood that other suitable means may be used to attach and detach the head, the tool herein shown and described is recommended because it is adapted to be secured in place for as along as one who frequently opens and closes the container desires, and can then be removed entirely to permit shipment of the container.

In the closure construction provided by the invention ring 3 not only reinforces the container at its end, where it is most subject to injury, but also is replaceable in case the bosses should become damaged. In order to provide ample reinforcement by this ring it is of heavy section, preferably being about two and one-half times as thick as the container shell. In this manner loss through scrapping of otherwise sound containers is minimized. These are substantial advantages over the constructions heretofore used.

According to the provisions of the patent statutes, I have explained the construction and mode of use of my invention, and have illustrated and described what I now consider to represent its best embodiment. However, I desire to have it understood that, within the scope of the appended claims, the invention may be practiced otherwise than as specifically illustrated and described.

I claim:

1. The combination with a metallic container open at one end and provided with a lip peripherally surrounding said end, of a

reinforcing ring encircling said container on the under side of said lip, a plurality of bosses struck out from said ring at spaced intervals and having their free edges formed to act as cam surfaces, means associated with said container holding said ring against said lip, a head for said end comprising a substantially flat central body portion and an upwardly extending side wall integral with said central body portion and telescopically fitting within the end and extending outwardly and downwardly to form a top portion and a skirt portion, said top portion overlying said lip and forming therewith a substantially enclosed annular chamber, a sealing gasket disposed in said chamber, and said skirt surrounding said ring and being provided with inwardly extending lugs adapted to cooperate with said bosses to draw the head into sealing engagement with the container when the head is rotated.

2. The combination with a metallic container open at one end and provided with a continuous horizontal lip surrounding said end, of a reinforcing ring encircling said container and held against the under side of said lip by a swell struck outwardly from said container, a plurality of bosses struck outwardly from said ring at spaced intervals and having their lower edges disposed angularly relative to the plane of said opening, a head for said end comprising a substantially flat body portion integral with an upwardly extending side wall telescopically engaging the container within said end and bent outwardly and downwardly from its upper end to form a top portion overlying said lip and a skirt surrounding said ring, said top portion forming with said lip a substantially enclosed annular chamber, a sealing gasket pressed into said chamber, and angularly disposed boss-engaging lugs projecting inwardly from the lower edge of said skirt adapted to slidably engage said bosses when the head is rotated upon said end to draw it into sealing engagement with the container.

In testimony whereof, I sign my name.

HEIMER W. MONSON.
